Thomas R. Evans, Inventor by
Geo. E. Brown, Atty.

United States Patent Office.

THOMAS R. EVANS, OF BLACKSBURG, VIRGINIA.

Letters Patent No. 101,599, dated April 5, 1870.

IMPROVEMENT IN CHURNS.

The Schedule referred to in these Letters Patent and making part of the same.

To all whom it may concern:

Be it known that I, THOMAS R. EVANS, of Blacksburg, in the State of Virginia, have invented a new and useful Improvement in Churns; and I do hereby declare that the following is a full, clear, and exact description of the same, reference being had to the accompanying drawings and letters of reference marked thereon, making a part of this specification, in which—
Figure 1 is a sectional elevation, and
Figure 2 a plan view.

This invention relates to a dasher composed of four or more perforated plates set crosswise of a box that slides lengthwise of the churn, said box being operated by toothed segments projecting downward from a transverse rock-shaft on or in the top of the churn, which shaft is worked by cranks or arms.

To enable those skilled in the art to make and use my invention, I now proceed to describe its construction and operation.

Similar letters in the drawings refer to like parts.

A is the churn;
B, the box, sliding on rollers;
b b b b, the perforated plates;
c c, racks on the upper edges of the sides of the box;
C C, the toothed segments which mesh with the racks;
D, the shaft from which the segments project;
d, the cranks extending from the shaft; and
E, a cross-bar uniting the ends of the cranks.
Arms may be employed instead of cranks.

What I claim as my invention is—

The combination of churn A, sliding box B, perforated plates *b*, racks *c*, segments C, shaft D, cranks *d*, and cross-bar E, all constructed and arranged to operate as described.

THOMAS R. EVANS.
